ANTIPANIC FASTENING DEVICE

William P. Ruth, Downs, Kans.

Application April 4, 1936, Serial No. 72,806

5 Claims. (Cl. 292—92)

This invention relates to anti-panic fastening devices or latches primarily designed for use on emergency exit doors of buildings frequented by large crowds of people and its general object is to provide a fastening device which can be easily and expeditiously disposed to unlatched position from the inside of the building merely by pressure applied to the releasing lever thereof in various directions and at any place transversely of the door, in that the lever extends across the door for disposal in the path of a person or persons coming in contact therewith by being forced toward the door, and the lever can be voluntarily actuated by pulling or pushing forwardly or rearwardly or by raising or lowering the same, yet the fastener holds the door closed and locked against being opened from the outside of the building to prevent unauthorized entrance.

A further object of the invention is to provide an anti-panic latching device for doors, that is simple in construction, inexpensive to manufacture, easy to install, requires minimum if any attention and lubrication, will not stick under any circumstances, will operate even though it becomes rusty and is extremely efficient in use and service.

This invention also consists in certain other features of construction and in the combination and arrangement of the several parts, to be hereinafter fully described, illustrated in the accompanying drawing and specifically pointed out in the appended claims.

In describing the invention in detail, reference will be had to the accompanying drawing wherein like characters denote like or corresponding parts throughout the several views, and in which:

Figure 1 is a fragmentary view illustrating my latching device in applied position.

Figure 2 is a transverse sectional view taken through a door and its frame, and illustrates the latching device in operative position in full lines and released in dotted lines.

Figure 3 is a view illustrating the application of a modified form of the invention.

Figure 4 is a sectional view taken through the modified form.

Referring to the drawing in detail, and particularly to Figures 1 and 2, it will be noted that the form of the invention illustrated thereby includes a latch having a base plate 1 with openings therein to receive securing means such as screws for fixing the plate 1 to the door A adjacent to the free portion thereof, as best shown

in Figure 2, and pivotally or hingedly secured to the base plate 1 is a latch plate 2 having formed with the outer end thereof a cam head 3 which provides a shoulder, as shown.

Secured to the jamb or abutment strip of the door, and in the path of the latch plate 2, is a keeper plate 4 having a cam head 5 providing a shoulder to receive the shoulder of the cam head 3 for latching the door in closed position.

Secured to the door adjacent to its hinge portion, is a bracket 6 which includes an outwardly directed ear 7 having an opening therein for the purpose of loosely receiving for slidable movement and swivel connection to the ear, one end portion of a releasing bar or lever 8 for the latch. The bar is held connected to the bracket through the instrumentality of a collar 9 that is fixed thereto by a set screw as shown, whereby the collar can be adjustably positioned on the bar.

The opposite end of the bar in the form as shown is provided with an opening or eye 10 to receive one eyed end of a link 11 which has its opposite eyed end received in an opening 12 in an ear 13 which is formed on or otherwise secured to the outer end of the latch plate 2 and disposed at right angles with respect thereto.

In order to hold the latch plate normally in latched position, there is provided a leaf spring 14 that has one of its ends fixed to the base plate 1 and its opposite end fixed to the latch plate 2, and due to the fact that the leaf spring is curved in the position shown, it urges the latch plate outwardly at all times to not only hold the latch in operative position, but when the door is being closed, the cam face of the head 3 will contact the cam face of the head 5 to move the latch plate 2, to a position for disposing the shoulder of the head 3 against that of the head 5, or to latched position, as best shown in Figure 2.

In Figures 3 and 4 there is illustrated the use of spring pressed bolt type latching means disposed at the upper and lower ends of the door A, for association with the stile and threshold of the door, and of course the lower latching means can have its bolt received in an opening in the floor adjacent to the door, as these latching means are for the purpose of holding the door in closed position and can be arranged or associated with any means for that purpose.

Secured to the door is a base plate 15 from which extends a spindle 16, the latter having a head thereon for holding a sleeve 17 rotatably mounted on the spindle, and projecting in opposite directions from the sleeve are arms 18 nor-

5 mally disposed vertically, with openings in the outer ends thereof, for the connection of one of the ends of rods 19 thereto, while the opposite ends of the rods are connected to the bolts 20 of the latching means 21 at the upper and lower ends of the doors, as shown.

10 The sleeve 17 has likewise formed thereon and rising therefrom in spaced parallel relation with respect to the uppermost arm 18, an arm 22 to which is loosely connected one end of a link 23 similar to the link 11, and the opposite end of the link 23 is loosely connected to the apertured end of a bar or lever 24 similar to the lever 8. The lever 24 is likewise received by a bracket 25 for swivel connection thereto, and for slidable movement therethrough.

15 From the above description and disclosure of the drawing, it will be obvious that in either form of the invention shown, movement of the releasing bar or lever which may be termed a floating bar, in various directions, will release the door and allow the same to be swung to open position.

20 It is thought from the foregoing description that the advantages and novel features of the invention will be readily apparent.

25 It is to be understood that changes may be made in the construction and in the combination and arrangement of the several parts, provided that such changes fall within the scope of the 30 appended claims.

What I claim is:

35 1. An anti-panic device for doors comprising latching means normally securing a door in closed position, a rigid bar extending across the door and having a swivel and sliding connection therewith at one of its ends, a link having loose connection with the latching means and the opposite end of the bar whereby upon moving the bar in various directions, the latching means will 40 be operated to released position.

45 2. An anti-panic device for doors, comprising latching means normally securing a door in closed position, a bracket secured to the door, a rigid bar extending across the door and having one end loosely connected to the bracket and mounted for slidable movement therein, a link

loosely connected to the opposite end of the bar and the latch means respectively for operating the latter to releasing position upon movement of the bar in various directions.

3. An anti-panic device for doors, comprising 5 latching means for normally securing a door in closed position and including keeper means, a spring pressed latch plate pivotally connected to the door and received by the keeper means, a bracket secured to the door and including an ear 10 having an opening therein, a rigid bar loosely mounted in the opening for slidable movement, means secured to the bar for connecting the latter to the ear, and a link loosely connecting the bar to the latch plate for releasing the latter 15 from the keeper upon movement of the bar in various directions.

4. An anti-panic device for doors comprising 20 latching means for normally securing a door in closed position and including a keeper plate, a cam head formed on the keeper plate, a base plate secured to the door adjacent the free portion thereof, a latch plate pivotally secured to the base plate, a cam head on the latch plate and cooperating with the cam head of the keeper plate, for holding the door in said position, spring means for urging the latch plate toward the keeper plate and to retain the latch in operative position, and a rigid bar extending across the 25 door and having one end loosely connected thereto, and its opposite end loosely linked to the latch plate for releasing the latter from the keeper plate upon movement of the bar in various directions.

5. An anti-panic device for doors comprising 30 latching means including spring pressed bolts secured to a door at the upper and lower ends thereof adjacent its free portion, means for actuating said bolts to released position, and a rigid 35 bar extending across the door and loosely connected thereto and loosely linked to the releasing means for operating the latter to releasing position upon movement of the bar in various directions.

WILLIAM P. RUTH. 45
